WEB CUTTING MECHANISM

Paul L. Tollison, North Plainfield, N. J., assignor
to Wood Newspaper Machinery Corporation,
Plainfield, N. J., a corporation of Virginia

Application March 9, 1946, Serial No. 653,401

4 Claims. (Cl. 164—66)

1

This invention relates to printing presses, particularly to folding and severing mechanism associated therewith especially in newspaper plants.

For many years it has been accepted as inevitable that a press room be extremely noisy during operation of the presses. It is now recognized that a high noise level is productive of unnecessary fatigue and possible impairment of hearing in those who must work under it. It is therefore a principal object of this invention to reduce press room noise level.

I have found that one of the principal sources of noise in a high speed press installation of the type usually found in newspaper plants is the normal operation of the knife box cheek woods. This noise derives from two phases of the cheek wood operation. The first and least objectionable is caused by the cheek wood striking the unsevered web of paper as rotation of the cutting cylinder causes the knife box to approach the folding cylinder. The other and most bothersome noise arises from the impact of the cheek woods with their stops in their outward travel along the knife blade after the severance of the paper. Accordingly, the particular objects of this invention are to provide an improved construction for the cheek pieces of the knife box that will avoid this principal source of noise and will, at the same time, be adapted for use in existing knife boxes as a repair or replacement for existing cheek woods, without making any substantial alterations.

An embodiment of my invention is described in connection with the appended drawings, in which:

Fig. 1 is a partial cross-section through the cutting cylinder 11 and folding cylinder 10 of the cutting couple of a high speed rotary press, taken at the moment of cutting action and illustrating an embodiment of my invention; and

Fig. 2 is a longitudinal section taken on the line 5—5 of Fig. 1.

As shown in Fig. 1, the severance of the paper 13 is accomplished by drawing it between the cutting cylinder 11 and the folding cylinder 10 of a cutting couple. The folding cylinder 10 is provided with one or more cutting rubbers 14 spaced to cooperate with a knife or knives 15 held in one or more knife boxes 12 on the cutting cylinder 11. To free the severed web 13 effectively from the knife 15, it has been well known for many years to provide the knife with extensible cheek pieces which move outward along the knife towards its cutting edge as the knife and cutting rubbers draw apart, thereby to push the web clear of the blade.

2

In the disclosed embodiment of my invention, these cheek pieces are represented by the cheek woods 16 on either side of the blade 15. These cheek woods are pressed outward from the axis 5 of the cylinder 11 toward the serrated cutting edge of the blade 15 by the post carried springs 17, but are retained within the knife box 12 by the stop shoulders 18.

The cheek woods 16 are provided at each end 10 with a dash pot control device which checks their return against the stop shoulders 18 under the influence of springs 17. This dash pot device, as illustrated in Figs. 1 and 2, comprises a connecting rod 23 which at one end is pivotally connected 15 to the cheek wood 16 by the pin 24 and at its other end carries a piston 25 slidable in a check cylinder 26. This cylinder is full of fluid, preferably of the sort used in hydraulic shock absorbers, and is closed at its inner end by the plug 27. It 20 is further provided with a system of passages connecting the spaces in the cylinder 26 above and below the stroke of the piston 25.

Passage 28 which opens into cylinder 26 a short distance above the bottom of the stroke of piston 25 is connected through the passage 29 to the passage 30 which opens into cylinder 26 above the piston 25 when the cheek wood 16 begins its outward motion under the influence of the springs 17. Fluid flows rapidly through passage 28 which 30 is of comparatively large diameter and thence through passages 29 and 30 also of comparatively large diameter from the bottom of the piston 25 to its top. Thus the initial outward motion of the piston 25 is scarcely checked at all by hydraulic action. However, as the cheek wood 16 35 nears its full extension, but before it comes in contact with the stop shoulder 18, the piston 25 closes off the opening of the passage 28 into the cylinder 26 and fluid trapped under the piston 25 must flow through the relatively restricted passage 31 into passages 29 and 30 in order to 40 reach the space at the top of the piston 25. Thus the rapid outward motion of the cheek wood 16 is checked and becomes an easing into contact 45 with the shoulder stop 18.

In order to permit the easy inward movement of the cheek wood 16 as it comes in contact with the unsevered web 13 at the next cutting operation, the relatively large passages 32 and 33 are 50 provided at the bottom and top of the stroke of piston 25. These passages 32 and 33 are interconnected through the ball check valve 34 which permits passage of fluid through it only from the top of the piston 25 to the bottom.

55 I have described this invention in connection

with an embodiment directly applicable to existing machinery. I do not wish to be limited to the details thereof but instead by the scope of the appended claims.

I claim:

1. In the cutting couple of a printing press, a knife box, a knife therein, cheek woods on either side of said knife, said cheek woods being movable parallel to said knife and perpendicular to its cutting edge, cylinders carried by said knife box, pistons running in said cylinders and connected to said cheek woods, the travel of said pistons in said cylinders being limited and thereby limiting the outward travel of said cheek woods so that the outer surfaces thereof do not pass beyond said cutting edge, passages connecting the inner and outer portions of said cylinders lying on opposite sides of said pistons and fluid in said cylinders.

2. The combination of claim 1 in which the passages connecting the inner and outer portions of each of said cylinders comprise two relatively large orifices into the inner portion of the cylinder, two orifices into the outer portion of the cylinder, one relatively large and one relatively small, a passage connecting one of said inner and the larger of said outer orifices, a ball check valve in said passage permitting outward flow only, an additional relatively large orifice intermediate said inner and said outer orifices but so located as to be outward of the outer surface of said piston except during the final portions of its outward travel, and a second passage interconnecting the other of said inner, the smaller of said outer and said additional orifices.

3. In the cutting couple of a printing press, a knife box, a knife in said knife box, cheek pieces on either side of said knife movable parallel to said knife and perpendicular to its cutting edge, springs for moving said cheek pieces outwardly relative to the cutting edge of said knife and a dashpot connected between said cheek pieces and said knife box for cushioning the outward movement of said cheek pieces.

4. In the cutting couple of a printing press, a knife box, a knife in said knife box, cheek pieces on either side of said knife movable parallel to said knife and perpendicular to its cutting edge, springs for moving said cheek pieces outwardly relative to the cutting edge of said knife, cylinders carried by said knife box, pistons running in said cylinders and connected to said cheek pieces, fluid in said cylinders and means forming restricted fluid passages between the portions of said cylinders lying on opposite sides of said pistons whereby the outward movement of said pistons and the connected cheek pieces is cushioned.
